LEONARD F. FULLER, OF PALO ALTO, CALIFORNIA, ASSIGNOR TO AUGUSTUS TAYLOR,
OF SAN FRANCISCO, CALIFORNIA.

RADIOTELEGRAPHY.

1,358,144.

Specification of Letters Patent. Patented Nov. 9, 1920.

Application filed April 14, 1919. Serial No. 289,947.

To all whom it may concern:

Be it known that I, LEONARD F. FULLER, a citizen of the United States, and a resident of Palo Alto, county of Santa Clara, 5 and State of California, have invented certain new and useful Improvements in Radiotelegraphy, of which the following is a specification.

The invention relates to radio telegraphy 10 transmission systems and particularly to a system employing a plurality of Poulsen arc converters.

An object of the invention is to provide a radio telegraphy transmission system embodying a plurality of arc converters, in 15 which each arc may be operated separately or in which the arcs may be coupled and operated in multiple.

Another object of the invention is to provide 20 a multiple arc transmission system signaling system.

The invention possesses other advantageous features, some of which, with the foregoing, will be set forth at length in the following description where I shall outline in full, that form of the invention which I have selected for illustration in the drawing accompanying and forming part of the present specification. The drawing is a 25 grammatic representation of one form of transmission system of my invention, but it is to be understood that I do not limit myself to such form of system.

Radio telegraphy transmission systems 30 employing the parallel operation of Poulsen arc converters have been proposed heretofore, but as far as I am aware, all of these prior systems propose the employment of two or more arcs operating on one antenna system. In the system of my invention, an 35 antenna system is provided for each arc, so that the arcs may be employed separately or in multiple. In accordance with my system, a complete transmitting set may be connected to each antenna, so that diplex sending 40 will be possible by operating the two sets on different wave lengths. When transmission to a particular point becomes difficult or when it is desirable to extend the 45 transmitting range of the station, the two arcs may be operated in parallel, with a very simple switching arrangement, to radiate energy from the two antennæ simultaneously. In accordance with my invention 50 signaling may be accomplished by al-

ternately throwing the currents in the two antennæ into and out of phase. The two antennæ are very close together, so that when the currents are in phase, their energies are added and signals are transmitted, 60 and when they are out of phase, the waves radiated from the two antennæ produce complete interference so that no energy reaches the receiving station.

The system shown diagrammatically in 65 the drawing comprises two Poulsen arc converters 2, fed by the D. C. generators 3 through the choke coils 4. One side of each arc is grounded and the other side of each arc is connected respectively to the antennæ 70 5—6 through the variable loading inductors 7—8. The two transmitting systems may be adjusted for different wave lengths and diplex signaling may be accomplished, and for this purpose each transmitting system is 75 provided with an independent signaling key of any suitable form, such as the keys 12 and 13 arranged to respectively short circuit a few turns of the loading coils 7 and 8.

When it is desired to transmit with increased power upon a given wave length, the arcs are operated in multiple. Inductively connected to the loading coils 7 and 8 and connected in series in the circuit 14, are the inductors 15 and 16. The circuit 14 contains a signaling key 17, and preferably a variable condenser 18, although the condenser may be omitted when desired and the coupling circuit thereby changed from a resonant circuit to a nonresonant circuit. 80 When the condenser 18 is omitted the coils 7—15 and 8—16 should be more closely coupled than when the condenser is employed, and the polarity of the inductors 15—16 85 must be reversed with respect to each other. 90

The two antenna systems are disposed so that there is a slight electrostatic coupling between them. This coupling usually exists in proper degree when the two antennæ are 100 erected on different tower systems, but are brought to the same radio station building. When the condenser 18 is used, the condenser and the inductances 15 and 16 are so adjusted that the coupling circuit has the same 105 frequency of oscillation as the antenna circuits, which are adjusted to the same frequency when multiple-arc sending is to be employed. With these conditions of coupling existing, the antenna currents will be 110 in phase opposition when the key 17 is open.

so that practically no energy will be radiated from the station. When the key 17 is closed, the antenna currents are brought into phase when the direction of current flow in coils 7-15 and 8-16 is such that an increasing current in one antenna will induce an increasing current in the same direction in the other antenna, and the coils are arranged to produce that condition. Signaling is, therefore, accomplished by closing and opening the key 17 which causes the antenna currents to be alternately thrown into phase and into phase opposition.

I claim:

- 15 1. A radio telegraphy transmission system, comprising a plurality of adjacent transmission systems, each having an arc converter and an antenna, and means for coupling said adjacent systems together.
- 20 2. A radio telegraphy transmission system, comprising a plurality of adjacent transmission systems, each having an arc converter, an antenna and an antenna loading coil, and a circuit coupling said loading coils together.
- 25 3. A radio telegraphy transmission system, comprising a plurality of adjacent transmission systems, each having an arc converter and an antenna, a circuit coupling said adjacent systems together, and means for interrupting and establishing the flow of current through said circuit.
- 30 4. A radio telegraphy transmission system, comprising a plurality of adjacent transmission systems, each having an antenna so disposed that an electrostatic cou-

pling exists between the antennæ and a circuit coupling said adjacent systems.

5. A radio telegraphy transmission system, comprising a plurality of adjacent transmission systems, each having an antenna, an antenna loading coil and an arc converter, a circuit coupling said loading coils, and means for establishing and interrupting the flow of current in said circuit. 45

6. A radio telegraphy transmission system, comprising a plurality of adjacent transmission systems, each having an antenna system, said antenna systems being electrostatically coupled, a circuit coupling 50 said antenna systems, and means for establishing and interrupting the flow of current in said circuit.

7. A radio telegraphy transmission system, comprising a plurality of arc converters, a separate antenna system for each converter, and a circuit electromagnetically coupling said antenna systems. 55

8. The method of radio signaling, which consists in establishing two antenna currents and throwing said currents alternately into and out of phase. 60

9. The method of radio signaling, which consists in establishing two antenna currents of equal frequency and value and throwing said currents alternately into phase and phase opposition. 65

In testimony whereof I have hereunto set my hand at Palo Alto, California, this 5th day of April, 1919.

LEONARD F. FULLER.
